UNITED STATES PATENT OFFICE.

BERNARD D. WILLIS, OF OAK PARK, ILLINOIS, ASSIGNOR TO AUTOMATIC ELECTRIC COMPANY, OF CHICAGO, ILLINOIS, A CORPORATION OF ILLINOIS.

SEMITAUTOMATIC TELEPHONE SYSTEM.

Application filed June 22, 1918, Serial No. 241,355. Renewed September 18, 1922. Serial No. 589,017.

To all whom it may concern:

Be it known that I, BERNARD D. WILLIS, a citizen of the United States of America, and a resident of Oak Park, in the county of Cook and State of Illinois, have invented certain new and useful Improvements in Semiautomatic Telephone Systems, of which the following is a specification.

My invention relates in general to improved means for setting up connections between subscribers in a system in which part of the connection is established by means of an operator's cord circuit and part by the use of so-called automatic switches.

More specifically, my invention relates to improved circuits and apparatus whereby a two-way trunk line may be used between a main exchange and a plurality of branch exchanges for setting up connections from the main exchange to any of said branches, and from any branch to the main exchange; and to accomplish this result by the use of a simplex operating circuit superimposed upon the conductors of said trunk line whereby a call from the branch to the main exchange may be reverted back to some subscriber in another branch over the same trunk line without interference or annoyance to the calling party.

In order to accomplish this and other new results I have connected the said trunk line in multiple with a selector switch in each of a plurality of branch exchanges, the selector in each exchange having a plurality of dead levels, corresponding in number to the number of other branch exchanges. These selectors are all operated in multiple by the operator in the main exchange, and only that selector which strikes a live level is effective to further extend the connection, while the rest of the selectors are left standing on the dead levels.

The drawings, comprising Figs. 1 and 2, show by means of the usual circuit diagrams a trunk line and sufficient apparatus in the main exchange and in one of the branch exchanges to enable the invention to be explained and understood.

In Fig. 1 of the drawings I have shown a cord circuit A which has access to an inter-office trunk line leading to toll selectors in various branch exchanges, one of said selectors being shown at E. This toll line is of the two way type, that is, a subscriber in any of the branch exchanges has access

to this trunk over the normals thereof and may signal the operator. I have shown no supervisory or other circuits associated with the answering end of this cord circuit, it being understood that this end of the cord may be arranged to connect with manual lines or trunks accessible to automatic switches in any known manner. The toll selectors E have access to toll connectors such as H (Fig. 2) in their respective exchanges. In each selector E there are a number of dead levels corresponding to the number of exchanges into which the toll trunk is multiplied, that is, if 2 is dialed over this trunk line then the toll selector in each exchange will step to the second level, which is dead in all except the #2 exchange, so that the operation of the switches in all except this No. 2 exchange will be ineffective to establish a connection. The toll connectors H have access in the usual manner to called lines such as shown at B (Fig. 2).

The called subscribers B in each exchange may also have access through the medium of any switches such as rotary connectors or selectors with the multiples of the toll trunk line for extending calls to the main office as will be explained.

I will now describe the operation of the system when a call is received by the operator and extended through the switches E and H to a called subscriber in one of the branch exchanges over the two way trunk line 10 and 11. The operator upon receiving a signal from any calling subscriber inserts the plug P' into the answering jack of the calling line and throws the listening key K to connect her head set X with said calling line. The calling subscriber then informs the operator of the wanted subscriber's number and the operator inserts the calling plug P into the jack J associated with one end of trunk line 10 and 11 leading to the branch exchanges. This insertion of the plug P into the jack J closes a circuit from ground through springs 7 and relay 8 to battery. Relay 8 upon energizing disconnects the windings of relay 9 from the trunk conductors 10 and 11 and connects said conductors to the tip and ring conductors of the jack J. A circuit is thereby closed from battery through the impulse springs of calling device C. D., springs of key K (now in operated position), key K', key K'', windings of relay 14 in multiple, 110

2
conductors 10 and 11 in multiple, windings 15 and 16 of the repeating coil in multiple, springs 17, springs 18 and 19, and relay 20 to ground through springs 21. At the same time that the circuit of relay 20 is thus closed a circuit is also closed for as many other line relays such as 20 as there are small exchanges, that is, there are a number of other relays similar to relay 20 connected 10 to the extension conductors 22 and 23 in the same manner, so that when the trunk such as 10 and 11 is seized from the main exchange, the line relays of a plurality of switches are energized simultaneously, each 15 line relay such as 20 being associated with a toll selector exactly similar to the toll selector E (Fig. 1).

The calling device may now be operated to send a plurality of impulses to line relay 20 corresponding to a digit of the called number. Relay 20, in response to this series of impulses, operates the vertical magnet 32 over a circuit extending from ground through springs 21, springs 25 and 26, 25 springs 28, springs 29 and 30, relay 31, and vertical magnet 32 to battery. Relay 24 energizes as soon as relay 20 pulls up to close springs 29 and 30 and to place ground through springs 33 on the private normal 30 contact 34 and its multiples in the banks of outgoing switches, and being slow acting, remains in operated position while relay 20 is vibrating its armature. The operation of magnet 32 steps the wipers 35-38 including 35 to the live or active level of the bank, in which are terminated trunk lines leading to connectors such as H. Relay 31 is energized in series with magnet 32, and being slow acting, remains energized during 40 this series of impulses, and as soon as the off normal springs 39 close a circuit is closed for the rotary interrupter relay 40 from ground through springs 33, springs 41 and 42, springs 39, and relay 40 to battery. 45 Relay 40, upon energizing, closes a locking circuit for itself at its upper armature, and prepares a circuit at springs 43 for the rotary magnet 44 which is closed at springs 41 and 45 as soon as relay 31 falls back after 50 impulses. Magnet 44 therefore energizes to step the wipers 35-38 to the first set of contacts of the elected level, and at the same time breaks the locking circuit of relay 40. If the trunk connected to this first set is 55 busy a ground will be present on the test contact engaged by wiper 37 so that as soon as magnet 44 deenergizes after the relay 40 falls back, a circuit will be established from ground on wiper 37, through springs 46 and 47, springs 48, springs 39, and relay 40 to battery, so that relay 40 is again energized 60 and the circuit of magnet 44 is again closed to step the wipers onto the contacts of the next trunk line. As soon as an idle trunk 65 line is reached no ground is found by wiper

37, and relay 49, which has heretofore been short circuited, energizes over a circuit from ground through springs 33, relay 49, springs 48, springs 39, and relay 40 to battery. Relay 49 being of high resistance does not 70 allow relay 40 to energize, but itself energizes to open the circuit of the operating magnet 32 at springs 28, prepares a locking circuit for itself at springs 50 and 46, which will later be supplied with ground 75 from the switch ahead, opens the circuit of relay 20, and switches the impulsive circuit from said relay 20 to the wiper 38 at springs 18 and 51. Relays 20 and 24 therefore deenergize and the operating magnets 80 and relays of the selector rest at normal.

Assume that the idle set of contacts seized in this level is connected to the connector switch H (Fig. 2), then as soon as relay 49 energizes a circuit is closed for the line relay 52 of said connector from ground through said relay, contact 53, wiper 38, springs 51 and 18, and over the previously traced circuit to and through the calling device C. D. of the cord circuit. Relay 52 energizes and closes a circuit for slow relay 54, which in turn energizes to place ground on the release trunk, which makes this switch busy at contact 37' and its multiples, and supplies ground to the holding circuit 95 of relay 49 of the selector.

The calling device C. D. may now be operated for the second digit of the called number, whereby the relay 52 operates to control the vertical magnet 55 over a circuit 100 from ground through springs 56 and 57, springs 58 and 59, springs 60, relay 61, and magnet 55 to battery. As soon as the switch takes its first vertical step, springs 60 open contact and springs 62 close so that the circuit of magnet 55 and relay 61 now leads through springs 62, springs 63 and 64, and relay 61 and magnet 55. The operation of magnet 55 causes the wipers 65, 66 and 67 to be stepped to some level of the connector 110 bank in which the desired line is located. Soon after the impulses for this digit cease, relay 61 falls back, and prepares a circuit at springs 63 and 68 for the rotary magnet 69 and slow relay 70 in multiple.

When the calling device is operated for the next or last digit of the called number, relay 52 again operates to control in this case a circuit extending from ground through springs 56 and 57, springs 58 and 59, springs 62, springs 63 and 68, springs 71, relay 70 to battery, and through springs 72 and 73 to magnet 69 in multiple with said relay 70 to battery. Relay 70 remains energized during this series of impulses and for a short interval thereafter, while magnet 69 operates to step the wipers to the contacts to which the desired line is connected.

Assuming that the called line were busy when the wipers test said line, then a circuit 125

- will be closed from ground on test contact engaged by wiper 67, through springs 74 and 75, springs 75' and 76, and busy relay 77 to battery, before relay 70 has time to fall back.
- 8 Relay 77 connects busy tone to the line circuit at springs 78, opens springs 71 in the operating magnet circuit, connects resistance 79 and battery to the line circuit to give a return circuit to the busy tone, and locks itself to ground through springs of relay 54. Should the called line be idle, however, then relay 77 will not energize and as soon as relay 70 falls back, a circuit is closed for the lower winding of relay 80 from ground through upper springs of relay 54, springs 81, lower winding of said relay, springs 82 and 75', springs 75 and 74, wiper 67, and relay 83 of the called party's line switch to battery. Relay 83 operates to disconnect the relays of the switch C' from the line circuit, and relay 80 upon energizing over this circuit connects the windings of back bridge relay 84 to the talking circuit, connects ground through springs 85 and 74 to the private wiper direct, and also connects said ground to its own upper high resistance winding to lock itself energized. The operator may now press her ringing key K' to project alternating current out over the previously traced operating circuit including relay 52 of the connector. This alternating current does not effect relay 52 but follows the branch path through the tuned alternating current relay 86 which operates to close a circuit for the ringing relay 87 through springs 88. Relay 87 now operates to connect the called side of the talking current to the generator R and to the resistance 79. After the ringing is discontinued and the called subscriber answers, relay 84 is operated over the called line circuit to close the springs 89 and 90 to cut the talking circuit through from the operator to the called line. The operator upon hearing the called subscriber's response, restores the listening key K and the calling and called subscribers may converse.
- After conversation the operator presses the release key K² to allow relay 52 of the connector to fall back and close the circuit of the release magnet 91 of the connector by opening the circuit of relay 54, which relay also removes ground from the holding circuit of the selector E, which in turn releases. The operator may then remove the plug from the jack J in readiness for a future call.
- As previously stated there are a plurality of selectors E, E', etc., connected in multiple to the trunk line 10 and 11. Now if the call had been to some other exchange than that in which subscriber B is located then the selectors E, E', etc., would have been operated to a different level and the connection would have been extended to a subscriber in some other exchange through the medium of some other switch E' for instance. Selector E, however, would reach a level in which the contacts are similar to those shown at 92, 93, 94 and 95 in Fig. 1. 70 Now as soon as the switch E cuts in on the first contact of this dead level then the switch will cut through by the energization of relay 49 in the usual manner and the dialing circuit will pass to relay 96 over wiper 75 38 and contact 94. Relay 96 will therefore energize in multiple with the line relay (similar to relay 52 of connector H) of the connector switch which has been seized by some selector E' which has not found a dead 80 level. Relay 96 energizes slow relay 97 to connect ground through springs 98, contact 93, wiper 37, springs 46 and 50, and relay 49 to battery over a previously traced circuit. The selector E and other similar selectors which have found a dead level will remain cut through to the contacts of that dead level, until the connection is released by the operator. It will be understood that each switch has as many dead levels as there are other switches connected to the trunk line so that if 2 for instance is dialed then only one switch will find a connector while the rest will all find dead contacts on that second level. 95
- Assume now that some subscriber such as B in any one of the branch exchanges desires to call the operator at A over the trunk line 10 and 11. This subscriber will extend a connection through a rotary connector, selector repeater or any other well known switch to the normal contacts 100, 101 and 34 (Fig. 1) and after testing said contacts to determine the busy or idle condition thereof, will cut through and connect a ground to contact 34, and springs of relays 24 and 49, and through relay 102 to battery. Relay 102 connects ringing current to the toll line conductors 10 and 11 through springs of relays 103, and disconnects the ground at springs 21 from the springs of line relay 20. The application of alternating current to the conductors 10 and 11 causes relay 9 to energize through current flowing in its windings in series. Relay 9 115 closes the circuit of the lamp 105 to signal the operator that a connection is desired, and also closes circuit for the righthand winding of relay 104 which energizes to close a new circuit for the lamp 105 and also 120 closes the springs 109. The closure of springs 109 at this time completes the simplex operating circuit of all the switches E', etc., except the switch E which is, of course, made busy by the ground on contact 125 34 from the occupying switch. This circuit may be traced to switch E', for example, from battery through the left hand winding of relay 104, springs 109, windings of relay 9 in multiple, conductors 10 and 11 in mul- 130

5 tiple, conductors 22 and 23 in multiple, windings such as 15 and 16 of the repeating coil associated with switch E' in multiple, 10 springs such as 18 and 19, and a line relay such as 20, to ground. It will be understood that in the same manner the circuit of the line relays of all the other selectors except E are closed in multiple and each relay energizes to close the circuit of its associated slow relay (similar to relay 24) to ground the release trunk and contact such as 34 to make the trunk line busy to further calls.

15 A further result of the connection to contacts 100, 101 and 34 is the closure of the line circuit through the connector switch in the usual manner, said circuit extending from ground through relay 103 of selector E, springs 106 of relay 49, winding 107 of repeating coil, contact 101, to and through 20 a series circuit or back bridge in the occupying connector, and back through contact 100, winding 108, springs 109, and relay 110 to battery. Relays 110 and 103 energize over this circuit.

25 Relay 103 disconnects the generator current from conductors 10 and 11 at springs 111 and 112, and closes a new point in the operator's side of the repeating coil at springs 113. Relay 110 closes the circuit of slow relay 114 which supplies a holding and busying ground to the release trunk and contact 34 and also maintains relay 102 energized.

30 The operator upon perceiving the lamp 105 glowing inserts the plug P in the jack J to answer the call. The insertion of the plug into the jack closes the circuit of relay 8 to open the circuit of the lamp 105 and switches the conductors 10 and 11 from the relay 9 and relay 104 to the line conductors leading to the jack J and through windings of relay 14 and the various keys to main battery through coil 13.

35 Assume now that this calling subscriber desires to have the call extended to some subscriber in one of the other branch exchanges which is accessible from another selector E' connected to this same trunk line 10 and 11. The operator may then by means 40 of her calling device C. D. operate the selectors in the same manner as explained in connection with the extension of a call to subscriber B, except that switch E will not operate and some other level of the selectors 45 will be selected, which level is live or has trunks therein only in the exchange desired. The operation of the calling device C. D. and the resultant operation of the switches E' and H' will cause no interference to the 50 calling party as all dialing and ringing is controlled over the simplex operating circuit as hereinbefore pointed out.

55 Now after conversation is completed between this calling branch exchange subscriber and the called subscriber, the calling

party will restore his receiver and release the switch which connected with the contacts 100, 101, and 34 in the usual manner. As soon as this switch releases, the series circuit of relays 103 and 110 is opened and 70 said relays deenergize. Relay 114 being slow acting remains energized for a brief interval after the deenergization of relays 103 and 110 and therefore holds relay 102 energized for a like time so that when relay 75 103 falls back, the alternating current is again connected to conductors 10 and 11 through front contacts of relay 102 and back contacts of relay 103. This alternating current flows through the windings of relay 80 14 in series and causes said relay to energize. Relay 14 upon energizing removes a short circuit from the relay 3, which relay energizes in series with the resistance 2 and battery to close a circuit for the lamp 4 as 85 soon as relay 14 again falls back and to prevent the closure of the short circuit of itself when said relay 14 falls back. The operator will therefore remove the plug P from the jack and release the extended connection in a manner before explained.

90 It should be understood that when a subscriber such as B, in one of the branch exchanges, desires to call another subscriber in his own exchange he will use local 95 switches of standard two wire type which are well known in the art to call such line and will only connect with the trunk lines 10 and 11 when desiring to call out of his own exchange. The switches E, E', etc., 100 and H, H', etc., are only for inter exchange calls.

95 It will therefore be seen that I have devised a very efficient and economical method of using a single two conductor two way 105 trunk line to extend connections in either direction over said trunk line between a main exchange and a plurality of branch exchanges. It is thought that the method of operation of a plurality of switches over a 110 single trunk line and eliminating all but one of the same on the first digit together with the means for making the trunk busy on calls to the main exchange and the lack of interference on reverting calls are all new 115 and highly efficient results together with other features pointed out.

120 I wish it understood that when a simplex circuit is referred to throughout the specification and claims, I refer to a circuit which includes the two sides of a trunk line in parallel and which extends from one pole of a battery to a point of an impedance bridged across a pair of conductors, through the two sides of the impedance and the two conductors in parallel and through another pair of impedances bridged across the conductors at another point and from a point of the other bridge to the opposite 125 pole of battery.

Having fully described and ascertained the features of my invention, what I consider to be new and desire to have protected by Letters Patent, will be pointed out in the appended claims.

What I claim as my invention is:

1. In a telephone system, a trunk line, a plurality of automatic switches associated with said trunk line, a simplex circuit superimposed on said trunk line, and means for operating said switches simultaneously over said superimposed circuit. 70
2. In a telephone system, a trunk line, a plurality of automatic switches individual to said trunk line, a simplex circuit superimposed on said trunk line, and means for operating said switches simultaneously over said superimposed circuit. 75
3. In a telephone system, a trunk line, means for extending connections in either direction over said trunk line, said means including a plurality of automatic switches associated with said trunk line, a simplex circuit superimposed on said trunk line, and means for operating a plurality of said switches simultaneously over said superimposed circuit. 80
4. In a telephone system, a trunk line, a plurality of automatic switches associated with one end of said trunk line, a simplex circuit superimposed on said trunk line, means for operating said switches simultaneously over said superimposed circuit, means for seizing said one end of the trunk line, and means automatically controlled by said seizure for closing said superimposed circuit. 85
5. In a telephone system, a trunk line, a plurality of automatic switches associated with one end of said trunk line, a simplex circuit superimposed on said trunk line, means for operating said switches simultaneously over said superimposed circuit, means for seizing said one end of the trunk line, and means automatically controlled by said seizure for closing said superimposed circuit to make said trunk line busy to further seizure at said one end. 90
6. In a telephone system, a trunk line, an automatic switch associated with said trunk line, a simplex circuit superimposed on the conductors of said trunk line, a relay in one branch of said circuit and controlled thereover to operate said switch to extend a connection to a called subscriber, and another relay in another branch of said circuit and controlled thereover to signal the called subscriber. 95
7. In a telephone system, a main exchange, a plurality of branch exchanges, a trunk line extending from the main exchange and having branches leading to each branch exchange, an automatic switch for each branch of the trunk line, a simplex circuit superimposed on the conductors of said 100
- trunk line, branches of said circuit superimposed upon said branches of the trunk line, and means associated with each branch of the circuit and controlled thereover for operating said switches to extend connections from said trunk line. 105
8. In a telephone system, a main exchange, a plurality of branch exchanges, a trunk line extending from the main exchange and having branches leading to each branch exchange, an automatic switch for each branch of the trunk line, a simplex circuit superimposed on the conductors of said trunk line, branches of said circuit superimposed upon said branches of the trunk line, and means associated with each branch of the circuit and controlled thereover for operating said switches to extend connections from said trunk line to said branch exchanges. 110
9. In a telephone system, a main exchange, a plurality of branch exchanges, a trunk line extending from the main exchange and having branches leading to each branch exchange, an automatic switch for each branch of the trunk line, a simplex circuit superimposed on the conductors of said trunk line, branches of said circuit superimposed upon said branches of the trunk line, and means associated with each branch of the circuit and controlled thereover for simultaneously operating said switches to extend connections from said trunk line. 115
10. In a telephone system, a two way trunk line having movable terminals for extending connections therefrom and fixed terminals for extending connections thereto, an automatic switch for controlling said movable terminals, a simplex circuit including said trunk line for operating said switch, means for establishing a connection with said fixed terminals and for applying ringing current thereto, and means controlled by the application of said ringing current for operating a signal at the opposite end of said trunk line and for automatically closing said operating circuit. 120
11. In a telephone system, a trunk line, comprising a pair of conductors, a plurality of automatic switches individual to said trunk line, a line relay for each switch, a circuit including the two conductors of said trunk line in parallel for energizing said relays, and means for controlling said circuit to operate said switches to extend connections from said trunk line. 125
12. In a telephone system, a trunk line comprising a pair of conductors, a plurality of automatic switches associated with said trunk line, a line relay for each switch, a circuit for each relay including the two conductors of said trunk line in parallel, means for controlling said circuit to operate said switches to extend connections from said trunk line to called subscribers' lines, and 130

another relay included in said circuit with each line relay for signalling the called subscribers.

13. In a telephone system, an operator's position, a two-way trunk line leading from said position and terminating at the opposite end in a plurality of automatic switches, a line relay for each switch, a circuit for said relays including the conductors of said 10 trunk line in parallel, and means at the operator's position for controlling said circuit to operate said line relays simultaneously to extend connections from the trunk line.

14. In a telephone system, an operator's position, a two way trunk line leading from said position and terminating at the opposite end in a plurality of automatic switches and a plurality of fixed terminals, a line relay for each switch, a circuit for said relays 20 including the conductors of said trunk line in parallel, means at the operator's position for controlling said circuit to operate said line relays simultaneously to extend connections from the trunk line, means for seizing any of said fixed terminals, and means automatically controlled by such seizure for closing said circuit.

15. In a telephone system, a two way trunk line extending from an operator's position to branch exchanges, means for establishing a connection with the branch exchange end of said trunk line from one of said branch exchanges and for signalling the operator at said position, and a switch 30 individual to said trunk line controlled thereover by the operator for establishing a connection from said trunk line to another of said branch exchanges without disturbing the connection from the first branch exchange.

16. In a telephone system, a line, several automatic switches having access to said line at the same end thereof, a simplex circuit individual to said line, and means involving the use of said simplex circuit for making said line busy to all other switches when seized by one of said other switches.

17. In a telephone system, a line accessible to several automatic switches, a plurality 50 of other switches individual to said trunk line to extend connections therefrom, a simplex circuit superimposed on the conductors of said trunk line for operating said other switches, said simplex circuit automatically closed when the line is seized by anyone of said first switches to control means for making said line busy to all of the rest of said first automatic switches.

18. In a telephone system, a trunk line, 60 an automatic switch therefor, a simplex circuit superimposed on the conductors thereof, a relay included in said simplex circuit to operate said switch to extend a connection to a called subscriber, and another relay included in said simplex circuit and ener-

gized thereover to signal the called subscriber.

19. In a telephone system, a trunk line, an automatic switch therefor, a simplex circuit superimposed on the conductors thereof, a relay included in said simplex circuit to operate said switch to extend a connection to a called subscriber, and another relay included in said simplex circuit and energized thereover to signal the called subscriber, said first relay controlled by direct current and said other relay controlled by alternating current.

20. In a telephone system, a two way trunk line, a plurality of switches individual to one end thereof for extending connections therefrom, an operator at the other end thereof, means for seizing the one end of said trunk when a connection is desired, and means controlled by the operator for operating said switches to extend a connection excluding all except one of said switches and the end of the trunk leading to the operator.

21. In a telephone system, a trunk line leading from an operator's position to a plurality of branch exchanges, automatic switches for said trunk in each exchange, means for seizing said trunk line at any branch exchange and for signaling the operator, and means controlled by the operator for operating an automatic switch in any other of said branch exchanges over said trunk line to extend a connection to a called party in that branch exchange over said trunk line without interfering with the connection to the trunk line from the first branch exchange.

22. In a telephone system, a trunk line having a plurality of branches at one end, each branch terminating in an automatic switch, means for transmitting impulses over said trunk line to operate said switches simultaneously, and local trunk lines terminated in different positions in said switches so that the local trunk connected with depends entirely on the particular digit transmitted.

23. In a telephone system, a trunk line having a plurality of branches at one end, each branch terminating in an automatic switch, a group of trunk lines terminated in a particular position in one of said switches, other groups of trunks terminated in the other switches, respectively, each group terminating in a different position in the associated switch, and means for operating all said switches simultaneously to the same position to select a particular group of trunks by means of one of said switches, or for operating all of said switches simultaneously to a different position to select a different group of trunks by means of another of said switches.

24. In a telephone system, a trunk line having a plurality of branches at one end,

- each branch terminating in an automatic switch, a live position and a plurality of dead positions in each switch, the dead positions in each switch corresponding to the live positions in the other switches, a local line terminating at the live position on each switch, and means for operating said switches simultaneously to any position to connect the trunk line with any desired one of said local lines.
25. In a telephone system, a trunk line having a plurality of branches at one end, each branch terminating in an automatic switch, a live level and a plurality of dead levels in each switch, the dead levels in each switch being the levels which correspond to the live levels in the other switches, a local line terminating in the live level at each switch, and means for operating said switches simultaneously to any level to connect the trunk line with any desired one of said local lines.
26. In a telephone system, a trunk line having two branches at one end, each branch terminating in an automatic switch, a local line terminating in a certain level of one of said switches, a second local line terminating in a different level of the other of said switches, and means for operating both switches simultaneously to either level to connect the trunk line with either local line by means of the associated switch.
27. In a telephone system, a trunk line having two branches at one end, each branch terminating in an automatic switch, a local line terminating in a certain level of one of said switches, a second local line terminating in a different level of the other of said switches, means for operating both switches simultaneously to either level to connect the trunk line with either local line by means of the associated switch, and a holding circuit for each switch terminating in the level which corresponds to the level of the other switch in which the local line terminates.
28. In a telephone system, a trunk line terminating at one end in an automatic switch, means including a second switch for connecting with said trunk line at the same end, means for automatically projecting ringing current over the trunk line when the connection is established, and means at the other end of said trunk line responsive to ringing current for completing a control circuit for said first switch.
29. In a telephone system, a trunk line terminating at one end in an automatic switch, means including a second switch for connecting with said trunk line at the same end, means responsive to the establishment of said connection for closing a circuit over said trunk line including the two sides thereof in series, and means at the other end of said trunk line responsive to the closure of said series circuit for closing a control circuit for said first switch including the two sides of said trunk line in parallel.
30. In a telephone system, a trunk line connected in multiple to a plurality of incoming automatic switches, each switch being located in a different exchange, a common operating circuit for said switches including a conductor of said trunk line, outgoing automatic switches in each exchange for connecting with said trunk line, and means for closing said operating circuit when the trunk line is connected with by an outgoing switch in any one of said exchanges.
31. In a telephone system, a trunk line connected in multiple to a plurality of incoming automatic switches, each switch being located in a different exchange, a common operating circuit for said switches including a conductor of said trunk line, outgoing automatic switches in each exchange for connecting with said trunk line, means for closing said operating circuit when the trunk line is connected with by an outgoing switch in any one of said exchanges, and means in the incoming switches in the other exchanges responsive to the closure of said circuit for making said trunk line busy to the outgoing switches in said other exchanges.
32. In a telephone system, a main exchange, and a plurality of branch exchanges, a trunk line extending from a manual switchboard at the main exchange to all of said branch exchanges, a toll switch at each branch exchange in which said trunk line terminates, means including another automatic switch controlled by a calling subscriber in one of said branch exchanges for connecting with said trunk line, and means at said switchboard for transmitting impulses over said trunk line to operate the toll switch at the proper branch exchange to extend the connection to the called line.
33. In a telephone system, a trunk line terminating at one end at a manual switchboard, a call signal for said trunk, means including an automatic switch controlled by a calling subscriber for connecting with said trunk line at the other end, means responsive to the completion of the connection for automatically projecting ringing current over said trunk line to cause the operation of said call signal, and means for automatically and permanently opening the ringing circuit before the operator answers the call.
34. In a telephone system, a trunk line terminating at one end at a manual switchboard, a call signal for said trunk, means including an automatic switch controlled by a calling subscriber for connecting with said trunk line at the other end, and means responsive to the completion of the connection for automatically projecting ringing current over said trunk line to cause the operation

of said call signal, operator's equipment for connecting said trunk line with a called line, a disconnect signal associated with said equipment, and means responsive to the replacement of the receiver by the calling subscriber for automatically projecting ringing current over said trunk line to cause the operation of said disconnect signal.

35. In a telephone system, a trunk line terminating at one end at a manual switch-board, an automatic switch controlled by a calling subscriber for connecting with said trunk line at the other end, operator's equipment for connecting said trunk line with a called line, a disconnect signal associated with said equipment, and means responsive to the replacement of the receiver by the calling subscriber for automatically projecting ringing current over said trunk line to cause the operation of said disconnect signal.

36. In a telephone system, a trunk line terminating at one end at a manual switch-board, a call signal for said trunk, means including an automatic switch controlled by a calling subscriber for connecting with said trunk line at the other end, means responsive to the completion of the connection for automatically projecting ringing current over said trunk line to cause the operation of said call signal, a ring cut-off relay, and means for automatically energizing said relay before the operator answers the call.

37. In a telephone system, a trunk line terminating at one end at a manual switch-board, a call signal for said trunk, means including an automatic switch controlled by a calling subscriber for connecting with said trunk line at the other end, means responsive

to the completion of the connection for automatically projecting ringing current over said trunk line to cause the operation of said call signal, and means also responsive to the completion of the connection for stopping the ringing operation before the operator answers the call.

38. In a telephone exchange system, an originating office, an outlying office, trunk lines extending between said offices, an automatic switch in said first office for selecting one of said trunk lines, responsive means individual to said trunk line at the outgoing end thereof, a signal associated with said trunk line at the incoming end thereof, means made effective by the seizure of said trunk line by said switch to operate said responsive means, and means under the control of said responsive means for operating said signal.

39. In a telephone exchange system, an originating office, an outlying office, trunk lines extending between said offices, a cord circuit at said second office for connection with said trunk lines, an automatic switch in said first office for selecting one of said trunk lines, responsive means associated with said trunk at the outgoing end thereof, a signal associated with said trunk line at the incoming end thereof, a second signal in said cord circuit, and means made effective by the seizure of said trunk line by said switch to operate said responsive means to thereby operate said first signal and effective upon release of said trunk line to operate said second signal.

Signed by me at Chicago, Cook County, Illinois, this 13th day of June, 1918.

BERNARD D. WILLIS.

- of said call signal, operator's equipment for connecting said trunk line with a called line, a disconnect signal associated with said equipment, and means responsive to the replacement of the receiver by the calling subscriber for automatically projecting ringing current over said trunk line to cause the operation of said disconnect signal.
35. In a telephone system, a trunk line terminating at one end at a manual switchboard, an automatic switch controlled by a calling subscriber for connecting with said trunk line at the other end, operator's equipment for connecting said trunk line with a called line, a disconnect signal associated with said equipment, and means responsive to the replacement of the receiver by the calling subscriber for automatically projecting ringing current over said trunk line to cause the operation of said disconnect signal.
36. In a telephone system, a trunk line terminating at one end at a manual switchboard, a call signal for said trunk, means including an automatic switch controlled by a calling subscriber for connecting with said trunk line at the other end, means responsive to the completion of the connection for automatically projecting ringing current over said trunk line to cause the operation of said call signal, a ring cut-off relay, and means for automatically energizing said relay before the operator answers the call.
37. In a telephone system, a trunk line terminating at one end at a manual switchboard, a call signal for said trunk, means including an automatic switch controlled by a calling subscriber for connecting with said trunk line at the other end, means responsive to the completion of the connection for automatically projecting ringing current over said trunk line to cause the operation of said call signal, and means for automatically and permanently opening the ringing circuit before the operator answers the call.
38. In a telephone exchange system, an originating office, an outlying office, trunk lines extending between said offices, an automatic switch in said first office for selecting one of said trunk lines, responsive means individual to said trunk line at the outgoing end thereof, a signal associated with said trunk line at the incoming end thereof, means made effective by the seizure of said trunk line by said switch to operate said responsive means, and means under the control of said responsive means for operating said signal.
39. In a telephone exchange system, an originating office, an outlying office, trunk lines extending between said offices, a cord circuit at said second office for connection with said trunk lines, an automatic switch in said first office for selecting one of said trunk lines, responsive means associated with said trunk at the outgoing end thereof, a signal associated with said trunk line at the incoming end thereof, a second signal in said cord circuit, and means made effective by the seizure of said trunk line by said switch to operate said responsive means to thereby operate said first signal and effective upon release of said trunk line to operate said second signal.

Signed by me at Chicago, Cook County, Illinois, this 18th day of June, 1918.

BERNARD D. WILLIS.

DISCLAIMER

1,532,849.—*Bernard D. Willis, Oak Park, Ill.* SEMIAUTOMATIC TELEPHONE SYSTEM. Patent dated April 7, 1925. Disclaimer filed January 8, 1928, by the assignee by mesne assignments, *Automatic Electric Inc.*

Hereby enters a disclaimer to claims 38, 36, and 37 in said specification which are in the following words, to-wit:

“38. In a telephone system, a trunk line terminating at one end at a manual switchboard, a call signal for said trunk, means including an automatic switch controlled by a calling subscriber for connecting with said trunk line at the other end, means responsive to the completion of the connection for automatically projecting ringing current over said trunk line to cause the operation of said call signal, and means for automatically and permanently opening the ringing circuit before the operator answers the call.”

“36. In a telephone system, a trunk line terminating at one end at a manual switchboard, a call signal for said trunk, means including an automatic switch controlled by a calling subscriber for connecting with said trunk line at the other end, means responsive to the completion of the connection for automatically projecting ringing current over said trunk line to cause the operation of said call signal, a ring cut-off relay, and means for automatically energizing said relay before the operator answers the call.”

“37. In a telephone system, a trunk line terminating at one end at a manual switchboard, a call signal for said trunk, means including an automatic switch controlled by a calling subscriber for connecting with said trunk line at the other end, means responsive to the completion of the connection for automatically projecting ringing current over said trunk line to cause the operation of said call signal, and means also responsive to the completion of the connection for stopping the ringing operation before the operator answers the call.”
